DRYING AND TUMBLING APPARATUS

Harry D. Forse, Anderson, Ind.

Application June 24, 1946, Serial No. 678,726

8 Claims. (Cl. 34—57)

1

This invention relates to improvements in drying and tumbling apparatus, which apparatus is especially adaptable for use in commercial laundries or like establishments where the material, such as clothes, to be dried is customarily brought to and taken from the drier in nets, bags or other suitable containers.

A procedure followed in some laundries and like establishments is to sort each customer's bundle as it is received, place the articles of each classification in a container, such as a net, and then dispatch the netted articles to various departments for suitable processing, after which the several classifications are reassembled for inspection, checking and packaging. The processing work in some of the departments may be carried out without removing the articles from their containers. But in other departments, as for instance, drying and tumbling, the articles must be removed from their containers. Consequently, at the termination of the processing operation, the articles must be returned to their container. This returning of the articles to the container from some of the present day drying and tumbling equipment is often a long drawn out, piece by piece removal. Quite often some of the articles are not recovered and, therefore, become intermingled with another customer's articles in a succeeding run. This loss or intermingling of articles results in considerable time being spent searching for lost articles and tends to create ill will if the customer's bundle is delivered with substitute articles or if some of the articles are missing.

Some of the tumblers now in use are provided with a centrally located door through which clothes are deposited in and removed from the drier cylinder. Devices of this kind are readily and easily loaded. The open end of the net or container is inserted in the door opening and the bottom of the net is then elevated to empty the net. However, removing the articles from the tumbler is an entirely different matter. This operation is usually carried out by an operator blindly groping or feeling around in the darkened tumbler for the various articles. Any attempt on the part of the operator to visually inspect the interior of the tumbler merely puts the operator between the source of outside light and the interior of the device, thereby reducing visibility. Moreover, even though lighting is provided for the interior of the device, the task of manually removing the articles is laborious and time consuming. Additionally, the complete emptying of the tumbler is entirely dependent upon the capri-

2

ciousness, whimsey or fallibility of an operator.

Accordingly, one of the principal objects of advantage and importance of the improved drier of this invention resides in the provision of means for economically constructing an efficient, sturdy and dependable device which may be easily loaded and unloaded and which may be visually inspected interiorly thereof when in unloading position.

10 Another object of advantage and importance is the provision of means for agitating or tumbling clothes or other articles when positioned within the improved drier and of utilizing a current of heated air to assist in the tumbling and agitating operation.

Still another object of importance is the provision of means for supporting the door of the drier in a horizontal position to function as a receiving table for articles about to be loaded into the device, and of loading the articles within the drier by merely moving the door thereof to closed position.

15 A still further object of importance and advantage is the provision of means for unloading the drier by opening the door whereupon the article supporting interior surface of the drier is concurrently moved into a position closely adjacent the door opening where it may be visually inspected by an operator.

20 A further object of importance is the provision of means for facilitating the sacking or netting of articles removed from the drier.

An additional object of advantage and importance is the provision of power means for unloading the improved drier as well as for opening and closing the loading door. Moreover the movement of the door to open or closed positions is synchronized with and is in ratio to the movement of the conveyor to and from its operative position.

25 Still another and further object of advantage and importance is the provision of means for automatically disconnecting the power supply line to the tumbling and agitating means concurrently with the application of power for emptying the improved device.

Additional objects of advantage and importance will become apparent as the following detailed description progresses, reference being had to the accompanying drawings, wherein

30 Figure 1 is a front elevational view of a drying and tumbling apparatus which embodies the invention.

Figure 2 is a vertical section thereof.

Figure 3 is a sectional view of a fragmental

portion of the apparatus taken on line 3—3 of Figure 2.

Figure 4 is a sectional view taken on line 4—4 of Figure 3, and

Figure 5 is an elevational view of a portion of the apparatus with the door thereof in open position.

Figure 6 is a view showing diagrammatically, the electric circuits for controlling the operation of the improved apparatus.

Referring more particularly to the drawings, the reference numeral 10 indicates generally the body of an illustrative embodiment of the invention. The illustrated body 10 comprises a substantially rectangular shell having a relatively flat front surface 11 in which a utility opening 12 is formed. The height of the opening 12 may be varied as desired but the width thereof is preferably coextensive with the width of the interior of the body 10, as is best shown by the dotted lines 13 in Figure 1, for reasons hereinafter more fully disclosed. Adjustable ports 14 located adjacent the top and bottom of the body 10 and connected by link 19 provide means for controlling the admission of dry air into and the expulsion of wet air from the interior of the body.

Hinged as at 15 to the front surface 11 of the body is a closure member 16 which in closed position covers the utility opening 12 and in open position, as is best shown in Figure 5, provides a receiving platform for material to be loaded into or expelled from the body 10. The central portion of the closure member 16 is deformed to provide a recess 17 into which articles of clothes positioned on the horizontal closure 16 tend to gravitate. The bottom of the recess 17 is cut away and opposed side edges of the aperture are turned to form flanges 18 which slidably support a panel member 20. A handle 21 secured to the panel member 20 provides a means for operating that member to open and close the aperture in the bottom of the recess 17.

Secured to the flanges 18 in spaced relation is a plurality of securing hooks 22 to which a net 23 or the like, may be detachably secured. The rear hooks 22 are preferably formed and positioned to disengage from the net 23 upon the upward rotation of the closure member 16.

Hingedly secured to the upper portion of the closure member 16 is a pair of supporting legs 25 which upon downward rotation of the closure member provide a supporting abutment for the free end of that member. Upon the upward movement of the closure member 16 to its opening closing position the legs 25 swing inwardly paralleling the surface of the closure member as is best shown in Figures 1 and 2.

Hingedly secured to the interior surface of the closure member 16 is a formed apron member 26. When the closure member is in vertical position the apron member 26 provides a continuation for the curved interior surface thereof as will hereinafter more fully appear. The apron 26 extends the full width of the utility opening 12 and may bear against the interior surfaces of the body 10. The apron 26 is biased clockwise by springs, not shown, and upon the opening of the closure 16 rotates slightly in a clockwise direction to provide a protective barrier preventing the overflow of articles positioned on the receiving platform. A pawl 27 engageable with an abutment 28 functions to rotate the apron 26 counterclockwise upon the movement of the closure 16 to closed position.

Pivotedly positioned within the body 10 is an endless belt conveyor indicated in its entirety by the reference numeral 30. The conveyor 30 is fixed to a shaft 31 which in turn is journaled in and extends through the sides of the body 10. The conveyor 30 comprises two side members 32 positioned in spaced parallel arrangement and extending normally from the front lower portion of the body 10 upwardly and rearwardly, as is best shown in Figure 2 where the upper end is supported by an abutment 34. Suitable rollers 33 are operably positioned at opposite ends of the parallel side members and span the space therebetween. The rollers 33 carry a previous endless belt 35, preferably of screen or link construction, and this is driven through a belt 36, pulleys 37, and gear reducing unit 38 by a motor 40. Fixed to each side member 32 is an upwardly and outwardly flared guide member 41 the free edge of which may slidably engage a side of the body 10 as is best shown in Figure 3. The guide members 41 function to direct the material being processed onto the moving belt 35 of the conveyor 30.

Secured to the lower ends of the conveyor side members 32 is an apron member 42 upon which the free edge of apron 26 rests when the apparatus is in operating position. The apron member 42 is substantially arcuate in section and functions as an abutment for and a continuation of the apron 26 for insuring delivery of articles onto the belt 35 at the lower end of the conveyor 30.

In the illustrative embodiment shown a shelf 43 extends rearwardly from the lower end of the conveyor 30 and the free end thereof is supported by standards 45. Suitably mounted upon the shelf 43 is a blower 46 and a motor 47 which are operably connected by a drive belt 48. A duct 50 extends from the blower 46 upwardly and rearwardly, paralleling the conveyor 30, and terminates in an elongated nozzle 51 directly beneath the previous belt 35 near the upper end of the conveyor 30. A suitable heater 52 is positioned intermediate the ends of the duct 50 to heat air forced therethrough. Two spaced parallel members 53 secured to the side members 32 provide a duct 55 between the upper and lower portions of the conveyor belt contiguous to the elongated nozzle 51. The duct 55 prevents the dissemination of the current which is forced upwardly through the upper portion of the conveyor belt 35.

Pivotedly secured to the floor of the body 10 is a pressure motor 56 the piston rod 57 of which is suitably secured to the shelf 43. The pressure motor 56 is connected to a pressure supply line 54 in which a solenoid actuated three-way control valve 59 is positioned. A normally closed pressure switch 64 is connected in the supply line 54 downstream of the control valve 59. In the illustrative embodiment shown, the pressure motor 56 functions to rotate the entire conveyor unit including the blower 46, duct 50, and heater 52 from operating position as shown in full lines in Figure 2 to discharge position as shown in broken lines. However, it will be apparent that the piston rod 57 may be connected to the conveyor 30 so that the blower, heater and duct remain stationary when the conveyor is rotated.

As previously stated the shaft 31 extends beyond the sides of the body 10, and secured to the protruding ends of shaft 31 and rotatable therewith are gears 58 which through idler gears

60 drive gears 61 to operate closure member 16. This gear train, which may be enclosed in housing 62, rotates the closure at a more rapid rate than the conveyor 30 is rotated, so that movement of the conveyor through its 45 degrees, 65 approximately, of travel results in approximately 90 degrees of rotation of the closure. Moreover the rotative movement of the closure member 16 and the conveyor 30 are synchronized to reach their terminal positions simultaneously.

The motors 40 and 47 are supplied with energy from a source, not shown, through circuit 66 which extends from control box 67 and through pressure actuated switch 64. The heater 52 and the solenoid control valve 59 are supplied through circuits 68 and 70, respectively, which circuits are connected into control box 67, as best shown in Figure 6.

Operation

The improved drier and tumbler of this invention may be operated substantially as follows:

Assume for instance that the device is cold and that the closure 16 is in vertical position as shown in Figures 1 and 2. Operation is initiated by closing the circuit 69 to the heater 52 as by depressing the proper push button on the control box 67. Following this action, or concurrently therewith, and while the energized heater is warming up, the circuit 70 to the solenoid valve 59 is energized by operating a second push button on the control box 67. The closing of circuit 70 energizes the solenoid valve 59 and admits operating pressure to flow into the pressure motor 56 thereby forcing the piston rod 57 upwardly to rotate the conveyor 30 clockwise and through the gear train, gears 58, 60 and 61, rotates the closure 16 from its vertical position, as shown in Figures 1 and 2, to its horizontal position as shown in Figure 5. The admission of pressure to the downstream side of solenoid valve 59 in addition to supplying operating pressure to the pressure motor 56 also operates the pressure actuated cut-out switch 64 and thereby opens circuit 66. It is to be noted that provision is also made for controlling circuit 66 through control box 67.

The closure member 16 is now in horizontal position as shown in dotted lines in Figure 2 wherein it functions as a receiving platform and the conveyor 30 is in vertical position immediately to the rear of the utility opening 12 where it may be visually inspected, as for stray articles or the like. However, the movement of the conveyor to its vertical position usually discharges all of the articles on the conveyor onto the descending closure member 16. With the closure member 16 in this position articles, such as garments, to be processed are deposited thereon. This may be done by emptying a net or other container onto the platform. Now, with the platform loaded, the proper push button on the control box is operated to deenergize the solenoid actuated valve 59 to exhaust lifting pressure from the pressure motor 56 whereupon the conveyor 30 and the closure member 16 concurrently move to the full line positions as shown in Figure 2. While this movement may be accomplished by gravity alone it is to be understood that biasing or pressure means may be employed where it is so desired.

Upon the counterclockwise rotation of the conveyor and closure members, the articles on the closure slide toward the apron 26 and as the pawl 27 of that member engages the abutment

28 the apron is rotated to precipitate the articles onto the belt 35 of the conveyor 30. The apron 42 which is fixed to the conveyor 30 also assists in assuring proper delivery of the articles.

As the closure and conveyor members move toward their operating positions the push button, on the control box, which controls circuit 66 may be operated to energize the conveyor and blower motors 40 and 47, respectively, when the pressure in the switch 64 has been reduced sufficiently to close the circuit. Or the operation of the push button controlling circuit 66 may be operated after the closure and conveyor members reach their operating positions.

The operation of the blower 46 now causes a strong current of heated air to be discharged from the nozzle 54 upwardly through the duct 55 and conveyor belt 35. And the operation of the conveyor 30 rotates the articles deposited on the lower end thereof and carries the lowermost ones upwardly and rearwardly into the stream of heated air. The current of heated air strips the articles from the conveyor belt and carries them forwardly and as it dissipates the articles drop upon the moving conveyor belt to continue the circulating process.

This circulating process continues as desired and the ports 14 may be adjusted to permit a desired discharge of moist air from the upper port 30 and to permit an intake of dry air through the lower port. Thus the circulation of used air may be controlled.

At the termination of the processing period the push button controlling circuit 70 is operated to energize the solenoid of valve 59 and as pressure is admitted to the pressure motor 56 and pressure actuated cut-out switch 64, circuit 66 is deenergized stopping motors 40 and 47 and starting the opening movement of the conveyor and closure members. The clockwise rotation of the closure and conveyor members cause the articles to slide over the apron 26 and onto the closure member 16. The length of the apron 26 and the span of the guide members 41 are coextensive 45 with the width of the opening 12 so that no articles remain in the body 10 or drop to the floor during the opening operation. Now, with the articles deposited on the horizontal closure member 16 and a net 23 secured to the hooks there-

50 beneath the panel 20 may be withdrawn, as shown in Figure 5, to drop the articles into the container. After the closure has been cleared of articles the panel 20 is replaced and upon a new batch of articles being placed upon the horizontal closure the above operation may be repeated.

It will be apparent that herein is provided an efficient and practically automatic drier and tumbler of improved design which may be mechanically loaded and unloaded. Moreover the most remote article supporting portion of the device is, when in discharging position, within easy reach or visual inspection of an operator.

As it will be apparent to those skilled in the art to which the improved device of this invention appertains that numerous changes and widely different embodiments of the invention may be made without departing from the spirit and scope thereof, it is intended that the embodiment shown in the drawings and the description thereof shall be interpreted as illustrative and not in a limiting sense. Reference is therefore to be had to the appended claims for a definition of the limits of the invention.

I claim:

75 1. A drying and tumbling apparatus comprising

ing, a body having an opening therein, closure means for said opening, an endless belt conveyor operably mounted therein so that articles placed thereon may be carried from one end toward the other, motor means for driving said conveyor, means for controlling the operation of said motor means, duct means disposed to direct a flow of air to remove articles from one end portion of the conveyor and deposit them on the opposite end portion of said conveyor, and means for moving said conveyor toward a vertical position adjacent the opening for the discharge of said articles.

2. The structure of claim 1, including driving means connecting said closure and said conveyor and operable for moving said closure concurrently with the movement of said conveyor.

3. The structure of claim 1, including driving means connecting said closure and said conveyor whereby the movement of the conveyor from operating to discharge positions moves the closure from the closed position to a substantially horizontal position for the reception of the articles to be discharged.

4. The structure of claim 1, including means for stopping the travel of the conveyor as it approaches the discharge position.

5. The structure of claim 1, wherein said endless belt is pervious and including means for directing a flow of air through articles on said pervious conveyor, and means for heating said air.

6. The structure of claim 1, including means for creating said flow of air.

7. The structure of claim 1, including means for creating said flow of air and additional means for heating said flow of air.

8. The structure of claim 1, including means for stopping the flow of air as the conveyor approaches the discharge position.
